Philip Cramer

UNITED STATES PATENT OFFICE.

PHILIPP CRAMER, OF NEWARK, NEW JERSEY, ASSIGNOR TO MAGDALENA SCHAEFER,
OF NEWARK, NEW JERSEY.

RULER FOR BLACKBOARDS.

1,252,243.

Specification of Letters Patent.

Patented Jan. 1, 1918.

Application filed September 2, 1916. Serial No. 118,161.

To all whom it may concern:

Be it known that I, PHILIPP CRAMER, a subject of the King of Bavaria, residing at Newark, in the county of Essex and State of 5 New Jersey, have invented certain new and useful Improvements in Rulers for Blackboards, of which the following is a specification.

My invention relates to time-saving rulers 10 for chalk-lining blackboards in schools.

The object of my invention is to provide a ruler which can be handled as easily as a plain straightedge, yet contains all the straightedges necessary to draw lines for 15 common writing and likewise for writing of musical notes without having to lift the ruler off the board.

The accompanying drawings will make this clear.

20 Figure 1 is a top view of my ruler showing principally the two ends and showing how two sets of ruling bars are connected by links to two middle-pieces.

Fig. 2 is a top view of one of the middle-25 pieces.

Fig. 3 is a side view of the same showing the links in end view.

Fig. 4 is a full size section on line $x-x$, Fig. 1.

30 Fig. 5 is a section of the ruler when in its second position.

Fig. 6 is a plan of one set of chalk-lines as used for common writing.

Fig. 7 is a plan of lines used for writing 35 musical notes.

Numerals 1, 2, 3, 4 represent four ruling bars of a T-shaped section, all slidably mounted upon two rods 5 and 6. Bars 1 and 2 are rigidly connected by plates 7 and 40 8, and bars 3 and 4 are likewise rigidly connected by plates 9 and 10. These two sets of bars are connected by links 11 to two middle-pieces 12. This arrangement gives six useful ruling edges. The rods 5 and 6 pass 45 each through one middle-piece with space allowed for longitudinal motion for each middle-piece. Moving the middle-pieces in certain directions will bring all links at right angles to the middle-pieces and move the 50 two sets of ruling bars apart, while pushing back of the middle-pieces will bring the ruling bars closer.

The spread ruler is used for making four or six lines for common writing and the 55 closed ruler for lines for musical notes.

Each middle-piece has a shoulder 13 which will terminate longitudinal motion by striking against the through-passing rod. This striking is timed to occur just after the center lines of the links have passed the 60 rectangular lines 14 as shown in Fig. 1, and to prevent untimely return motion of the middle-pieces two contracting springs 15 and 16 attached to the two sets of ruling bars with a tendency of closing the ruler are 65 employed. The action of the springs would move the links in the directions indicated by arrows 17, which movement is prevented by the shoulders 13 in the middle pieces and it requires force to close the ruler. 70

Little rubber feet 18 assist in keeping the ruler from sliding.

The ruler when used is pressed against the board with one hand and the other hand guides the chalk. 75

The different positions in which the chalk can be held are indicated under numeral 19. Line 20 indicates the surface of the board.

What I claim is:

1. In a ruler for chalk-lining blackboards, 80 a plurality of ruling bars secured together in pairs, means for normally drawing said pairs together, and means for separating said pairs against the action of the first mentioned means.

2. In a ruler for chalk-lining blackboards, 85 a plurality of bars secured together in pairs, operating means located between adjacent pairs of bars, and means connecting said operating means with adjacent pairs of bars whereby said pairs can be drawn together or separated. 90

3. In a ruler for chalk-lining blackboards, 95 a plurality of ruling bars secured together in pairs, a plurality of sliding bars located between adjacent pairs of ruling bars, and means connecting said sliding bars and said pairs of ruling bars, whereby said pairs of ruling bars can be drawn together or separated. 100

4. In a ruler for chalk-lining blackboards, a plurality of ruling bars secured together in pairs, a plurality of sliding bars located between adjacent pairs of ruling bars, and a plurality of spaced links connecting said sliding bars and said pairs of ruling bars whereby the latter may be drawn together or separated. 105

5. In a ruler for chalk-lining blackboards, 110 a plurality of ruling bars secured together

in pairs, means for normally drawing said pairs together, a plurality of sliding bars located between adjacent pairs of ruling bars, and means connecting said sliding bars 5 and said pairs of ruling bars, whereby the latter can be drawn together or separated.

6. In a ruler for chalk-lining blackboards, a plurality of ruling bars, secured together in pairs, a spring attached to adjacent pairs 10 of ruling bars for normally drawing the same together, a plurality of sliding bars located between adjacent pairs of ruling bars, and a plurality of links connecting said sliding bars and said pairs of ruling 15 bars whereby the latter can be drawn together or separated.

7. In a ruler for chalk-lining blackboards, a plurality of ruling bars, means connecting said bars in pairs, and means located between adjacent pairs of ruling bars for 20 drawing together or separating said pairs of bars.

8. In a ruler for chalk-lining blackboards, a plurality of ruling bars, plates connecting 25 said bars in pairs, a plurality of sliding bars located between adjacent pairs of ruling bars, and means connecting said pairs of ruling bars and said sliding bars whereby said pairs of ruling bars can be drawn together or separated.

9. In a ruler for chalk-lining blackboards, a plurality of ruling bars, plates connecting said bars in pairs, a plurality of sliding operating bars located between adjacent pairs 35 of ruling bars, and links connecting said sliding bars and pairs of ruling bars for drawing together and separating said pairs of bars upon movement of said sliding operating bars.

40 10. In a ruler for chalk-lining black-

boards, a plurality of ruling bars, plates connecting said bars in pairs, rods on which said bars are mounted to slide, and means for drawing together or separating said pairs of bars.

45

11. In a ruler for chalk-lining blackboards, a plurality of ruling bars, means connecting said bars in pairs, operating bars located between adjacent pairs of bars, means connecting said operating bars and said pairs of ruling bars, whereby upon movement of said operating bars said pairs of ruling bars can be drawn together or separated, and means for limiting the movement of said operating bars.

55

12. In a ruler for chalk-lining blackboards, a plurality of ruling bars, plates connecting said bars in pairs, rods on which said bars are mounted to slide, and means for drawing together and separating said 60 pairs of bars.

13. In a ruler for chalk-lining blackboards, a plurality of ruling bars, plates connecting said bars in pairs, rods on which said bars are mounted to slide, sliding operating bars located between adjacent pairs of ruling bars, and links connecting said sliding operating bars and said pairs of ruling bars, whereby said pairs of ruling bars can be drawn together or separated 70 upon movement of said sliding operating bars, and means for limiting the movement of said operating bars.

In testimony whereof I affix my signature in presence of two witnesses.

PHILIPP CRAMER.
